UNITED STATES PATENT OFFICE.

WILLIAM R. TATE, OF BROOKLYN, NEW YORK, ASSIGNOR TO TATE SAFETY WINDOW SCAFFOLD CORPORATION, A CORPORATION OF NEW YORK.

WINDOW-WASHER'S SCAFFOLD.

Application filed March 27, 1925. Serial No. 18,811.

This invention relates to scaffolds, and has for one of its objects the provision of a device of this character which shall be especially adapted for use by window washers, which 5 shall be adapted to be readily secured in position for use, and which shall be adapted to be compactly folded for storage or transportation.

A further object of the invention is the 10 provision of a scaffold of the character stated which shall be simple and exceptionally strong and durable, and which shall be inexpensive to manufacture.

With the above and other objects in view, 15 the invention consists of the construction, combination and arrangement of parts hereinafter fully described and claimed, and illustrated in the accompanying drawings, wherein:

20 Figure 1 is a view in side elevation of the scaffold in position for use.

Figure 2 is a top plan view of the scaffold in position for use.

Figure 3 is a sectional view taken on the 25 plane indicated by the line 3—3 of Figure 2.

Figure 4 is a sectional view taken on the plane indicated by the line 4—4 of Figure 1.

Figure 5 is a sectional view taken on the plane indicated by the line 5—5 of Figure 1.

30 Figure 6 is a sectional view taken on the plane indicated by the line 6—6 of Figure 1.

Figure 7 is a bottom plan view of the scaffold in folded condition.

Figure 8 is a sectional view taken on the 35 plane indicated by the line 8—8 of Figure 7.

Figure 9 is a detail sectional view taken on the plane indicated by the line 9—9 of Figure 2, and

40 Figure 10 is a detail sectional view taken on the plane indicated by the line 10—10 of Figure 3.

Corresponding and like parts are referred to in the following description, and designated in the accompanying drawings by similar 45 reference characters.

In the drawings, 1 indicates the wall, 2 the window sill, and 3 the window frame of a residence, office building or the like.

The scaffold comprises a platform 4 which 50 embodies a base frame 5, spacing bars 6 positioned upon and secured to the lateral sides of the base frame, and floor strips 7 positioned upon and secured to the spacing strips 6. The frame 5 is of rectangular formation

and is preferably made of angle iron. The 55 platform 4 is provided with a guard which consists of uprights 8 having their lower ends removably positioned in sockets 9 in the outer corners of the platform, an outer horizontal rail 10, and side horizontal rails 11. 60 The uprights 8 and rails 10 and 11 are preferably made of metal and the rails 10 and 11 are secured to the upper ends of the uprights 8 by couplings 12.

A bracket 13 which is also preferably made 65 of angle iron and which is pivoted by rivets or bolts 15 to the lateral sides of the base frame 5 at points outwardly beyond the inner side of this frame comprises a horizontal member 15 vertical members 16 and downwardly and inwardly inclined brace members 17. The brace members 17 extend downwardly from the upper ends of the side members 16 and are secured at their lower ends to the horizontal member 15 by rivets 18. 70 The bracket 13 is a one-piece structure. It extends transversely of the platform 4, and is adapted to contact with the outer side of the window sill 2 when the scaffold is in position for use. Blocks 19 which are secured 75 to the inner side of the bracket 13 at the lower corners thereof engage the outer side of the wall 1 in order to obviate any tendency of the bracket to rock inwardly when the scaffold is in position for use and a 80 workman is standing upon the platform 4.

A clamp member 20 is adjustably secured 85 to the platform 4 by bars 21 which are slidably mounted upon the platform between the base frame 5 and the floor strips 7. The 90 bars 21 are provided with openings 22 and the floor strips 7 are provided with openings 23. Pins 24 which pass through the openings 23 of certain of the floor strips 7 and through the openings 22 in the bars 21, secure the clamp member 20 in adjusted position. The adjustment of the clamp member 20 is in the direction of and away from the bracket 13 in order to adapt the scaffold for use on buildings having walls of different 100 thicknesses. The clamp member 20 is connected to and depends from the inner ends of the bars 21. This connection is established by hinges 25 which are so arranged that clamp member 20 may only be moved in 105 the direction of the bars 21. When the scaffold is in position for use, the clamp member 20 contacts with the inner side of the

window sill 2. Padded blocks 26 are secured to the lower corners of the clamp member 20 for contact with the inner side of the wall 1, and prevents the clamp member from having any rocking movement on the window sill 2. The clamp member 20 is of rectangular formation, and is preferably made of angle iron. It is a one-piece structure and is provided with cross braces 27.

10 Struts 28 which are pivoted at 29 to brackets 30 secured to and depending from the outer corners of the base frame 5 and which rest at their lower ends upon the horizontal member 15 of the bracket 13, support the outer side of the platform 4. The lower ends of the struts 28 are detachably connected to the bracket 13 by hooks 31 pivoted to the side members 16 of the bracket and removably engaged with eyes 31^a carried by the struts.

As the bracket 13 is pivoted to the platform 4, as the struts 28 are pivoted to the platform and detachably connected to the bracket, as the bars 21 are slidably connected to the platform, and as the clamp member 20 is hinged to the bars, these parts may be compactly folded in the manner shown in Figures 7 and 8. Due to the fact that the struts 28 support the outer side of the platform 4, and due to the manner in which the bracket 13 and clamp member 20 engage opposite sides of the wall 1 and window sill 2, the scaffold is positively held against casual movement while in applied position.

It should be understood that the drawings are merely illustrative and do not pretend to give exact proportions. Furthermore, the said drawings are illustrative of a preferred construction, it being my expectation that

various changes and modifications may be made without departing from the spirit and scope of my invention.

What is claimed is:—

1. A scaffold comprising a platform, a bracket pivoted to the platform for folding against the same and normally depending from the platform, said bracket having an outwardly directed flange, struts pivoted to the platform and detachably connected to the flange on the bracket for folding against the latter, bars connected to the platform, and a clamp member on the same side of the scaffold as the bracket pivoted to the bars and foldable against them. 45

2. A scaffold comprising a platform provided with depending lugs at the outer corners thereof, a bracket pivoted to the platform adjacent the inner side thereof and depending therefrom and having an angle iron base, struts pivoted at their upper ends to said lugs and having their lower ends resting upon the said base, a clamp member to coact with said bracket, and means connecting the clamp member to the platform 60 on the same side thereof as the bracket. 55

3. A scaffold comprising a platform, means to secure the same to a support including a bracket pivoted thereto for folding against the platform an outwardly directed flange on the bracket, struts longer than the bracket engageable with said flange to maintain the bracket in contact with a support, and means pivoting said struts to the platform in offset relation to the bracket 70 in the folded position of the latter whereby the struts may be folded over the bracket in the collapsed form of the scaffold. 75

In testimony whereof I affix my signature.

WILLIAM R. TATE.
